UNITED STATES PATENT OFFICE

DESIGN FOR A COMBINATION GARMENT

Dorothy B. Barbour, Framingham Center, Mass.

Application September 2, 1937, Serial No. 71,437

Term of patent 7 years

To all whom it may concern:

Be it known that I, Dorothy B. Barbour, a citizen of the United States, residing at Framingham Center, county of Middlesex, and Commonwealth of Massachusetts, have invented a new, original, and ornamental Design for a Combination Garment, of which the following is a specification, reference being had to the accompanying drawings, forming a part thereof.

Fig. 1 is a plan view of a garment embodying the design in outspread condition and Figs. 2 and 3 are, respectively, front and rear elevations showing the garment as it appears when applied to a wearer.

The dominant features of my design reside in the specific configuration of a combination garment shown in outspread position in Fig. 1, having lateral fullness along the meeting horizontal bottom and top edges of the two main upper and lower sections, presenting to the garment, when draped as shown in Figs. 2 and 3, a shaped and defined waist in the region of the juncture of said sections and a draping fullness at the lower portion of the upper section affording the latter a distinctive blouse effect, the lower or skirt section having a substantially greater total area than the upper or blouse section, being of at least equal vertical extent therewith and being of at least one-third greater total lateral extent and so related to the upper section as to project extensively beyond both vertical side edges of the upper or blouse section, in the outspread position of the garment, said lower or skirt section overlapping at the rear of the garment in its worn position, and having broad pendant sash-like securing ties at its upper side edges further emphasizing the fashioned waist appearance and draped character of the garment as a whole.

I claim:

The ornamental design for a combination garment, substantially as shown and described.

DOROTHY B. BARBOUR.
